UNITED STATES PATENT OFFICE.

JOHN R. MEADOWCROFT, OF MONTREAL, QUEBEC, CANADA.

ALARM-ACTUATING APPARATUS.

1,338,146.

Specification of Letters Patent. Patented Apr. 27, 1920.

Application filed September 17, 1917, Serial No. 191,808. Renewed October 13, 1919. Serial No. 330,525.

To all whom it may concern:

Be it known that I, JOHN ROBERT MEADOWCROFT, a subject of the King of Great Britain, and resident of the city of Montreal, in the Province of Quebec, Dominion of Canada, have invented certain new and useful Improvements in Alarm-Actuating Apparatus; and I do hereby declare that the following is a full, clear, and exact description thereof.

My invention relates to apparatus forming a component part of automatic fire extinguishing systems, and more particularly the automatic alarm apparatus of the extinguisher systems for the interior of buildings and other structures liable to destruction by fire, the alarm being operated heretofore by the flow of the water not only upon the actual opening of the sprinkler system, but also in the event of the main water controlling valve of the system being disturbed by water hammer or other causes producing a sufficient light momentary abnormal pressure.

The object of my invention is to prevent disturbance of the main valve of the alarm by any other causes than actual opening of the sprinkler system.

To this end the invention consists of a particular relative arrangement of the main and auxiliary valves of the alarm, and the coaction therewith of an improved controlling mechanism of the retarding chamber, the effect of which latter is to retard the water between the main alarm valve and the circuit closers, and at the same time provide a quick discharge of the water from this retarding device in the event of momentary abnormal valve pressures occurring intermittently, owing to water hammer for instance.

More specifically summarizing the invention, I have an arrangement of coöperating alternating check valves adapted to normally provide an ample discharge for the accumulated water during the intermissions in a series of abnormal water pressures, and these valves admit to the retarding chamber the water released by the opening of the auxiliary valve. This auxiliary valve is of special form essential to the proper double seating thereof, and is referred to hereafter as a flexible self-adjusting metal valve, the self-adjusting feature being inherent owing to the fact that, after being adjusted on one seat, it will adjust itself to a second seat even

though the seats may be out of the same plane or parallel planes, because of improper grinding for instance.

For full comprehension, however, of my invention reference must be had to the accompanying drawings in which similar reference characters indicate the same parts, and wherein:

Figure 1 illustrates my improved alarm apparatus in elevation with parts in vertical sectional view;

Fig. 2 is a detail vertical sectional view of the valve;

Fig. 3 is a horizontal sectional view thereof taken on line 3—3 Fig. 2;

Fig. 4 is a detail vertical sectional view taken on line 4—4 Fig. 3; and

Fig. 5 is a transverse sectional view of the throw-off arm of the auxiliary valve.

Although I illustrate the specific construction of the retarding device, I do not claim it *per se* as it forms the subject-matter of a separate application.

The alarm valve proper consists of a casting 2 having a main water inlet 3 controlled by a main valve 10, and an auxiliary water inlet or by-pass 12 controlled by an auxiliary valve 13. The main valve has a preponderance of pressure exerted on the side 80 thereof away from the inlet 3 by means of an annular duct 14 in its seat and having a port 15. This main valve is, by this means, made a differential valve owing to the fact that the diameter of inlet 3 is less than the 85 effective opposite pressure area. These differential areas are represented by the diameter of port 3 on one side and on the opposite side the corresponding opposite diameter supplemented by the annular duct 14. An important feature of my invention is that I provide for the positive supply of the first or the first few sprinkler heads 90 opened, through the by-pass, the auxiliary valve, according to my invention, having 100 imparted to it a tendency to remain open as long as water flows through it.

The auxiliary valve coacts with this main valve and as will be presently shown, the main valve absolutely prevents the auxiliary valve from closing while the main valve is open, and in the event of the remote contingency of the auxiliary valve lagging, it will inevitably be disturbed from its seat upon the slightest movement of the main 110 valve, thus insuring the effectiveness of both alarm ports, when an alarm is required.

Referring more specifically to these valves: The main valve has a central hub or boss 16 with a diminished and screw-threaded upper end to receive a retaining nut 17 which prevents complete separation of the valve from a lever 18 fulcrumed on pin 19 journaled in seats 20 within the valve-casing. A throw-off arm 21 for carrying the auxiliary valve is located in the path of the main valve the lever 18 being forked to straddle the butt of this throw-off arm. This arm 21 is of triangular cross-section as shown in Fig. 5 and the butt is provided with an inclined shoulder 22 conforming to and lying in close proximity with an inclined face of lever 18, this inclined face being presented by a portion 23 of the lever bent at an angle to the length thereof.

This throw-off arm has a stop which comes in contact with the fixed stop 31 when it is thrown over as will be presently shown. This fixed stop 31 is cast on the inside of a cap 32 of the casing. The throw-off arm carries the auxiliary valve of which I will give a full detail description as it is extremely essential to the proper working of the apparatus. In order to obtain a proper degree of accuracy in the seating of the valves and the necessary sensitiveness to insure the positive unseating of the auxiliary valve at the slightest increase of water pressure, the outlet of the by-pass or auxiliary inlet 12 is substantially vertically disposed, and above the edge of the main valve at the diametrically opposite side from the fulcrum pin 19. This outlet has a bushing which serves as a seat for the auxiliary valve. The by-pass has a short pipe 25 with the edge at one end beveled as at 26 and its opposite end formed with a shoulder 27 and screwed into a seat 28 in the wall of the by-pass, such wall being thickened for the purpose and having a duct 29 the outer end of which is connected to a pipe system 40 to which the duct 15 is also connected as shown in Fig. 1 and the system is connected to the retarding chamber and the alarm sounding or indicating apparatus.

My flexible self-adjusting metal valve consists of a circular valve body 13 having a central circular boss 90 at one side and its rim screw-threaded to receive a flanged collar 92 which clamps the diaphragm 93 over a concavity 94 communicating with an axial hole 95; the head of this valve being of reduced diameter and screw-threaded to receive a nut 96. The portion of the body between the circular boss 90 and rim 91 has a hexagonal exterior 97 to facilitate the clamping of the diaphragm in place. This valve is connected to the free end of the throw-off arm by the circular boss being seated in a circular hole in the end 98 of the arm which is bent to lie normally parallel with the face of the bushing 24, this bush-

ing serving as a seat for this valve. It is important to so construct and assemble the by-pass 12, pipe 25, bushing 24, the bent end 98 of the throw-off arm and the auxiliary valve, that when the clamping ring 92, which is in effect the rim of the valve is seated on bushing 24, the diaphragm 93 will be slightly spaced from the mouth of the pipe 25, the diaphragm being normally caused to close the mouth of this pipe by the pressure of the water on the upper side of the auxiliary valve acting through the hole 95. This particular construction and arrangement of parts constitutes this valve a flexible self-adjusting one; and owing to the flexibility of the diaphragm 93 an accurate grinding of the two seats covered by this valve is not necessary.

The alarm-retarding apparatus proper consists of a retarding chamber 50 and an accumulating chamber 51, a single casting preferably embodying the accumulating chamber and approximately half of the retarding chamber. The other half of the latter consists of a casting composed of a member 52 of the wall of the casing having an oblique partition 53 inclosing a chamber sub-divided by a wall 54 into inlet and outlet sub-chambers 55 and 56, respectively. The inlet chamber 55 has the piping system 40 connected thereto by a tail-piece 60 clamped in place by a coupling 61 serving as a retaining means for a strainer 62, the discharge from this chamber being of diminutive capacity presented by a bushing or plug 63 screwed into a tapped hole 64 in partition 53 and having an opening 66 therethrough of small bore; the strainer being for the purpose of preventing sediment in the water of the system from blocking this port 66. The outer side of this plug or bushing relatively to the inlet chamber 55 has an annular shoulder encircling the port 66 and has a narrow top to facilitate the seating of one of the alternating valves. The outlet from chamber 50 to the sub-chamber 56 is through a relatively large port 68, and a correspondingly large port 69 acts as a discharge from this sub-chamber 56. The partition 53 between ports 66 and 68 has a post 70 upon which a lever is fulcrumed between its ends as at 71 such ends being of different lengths, the short end extending over port 68 and carrying a valve 72 and the long arm extending over port 66 and being counter-weighted as at 73 and carrying a valve 74.

This casting is detachably fastened in place upon the main casting by bolts 75 and nuts 76.

The accumulating chamber is preferably located above the retarding chamber and communication is effected between them through a casting 80 screwed into an opening 81 in an upwardly concaved partition 82

separating this chamber from the retarding chamber. This casting has a relatively small central port 83 and a series of fingers 84 supporting a downwardly concaved 5 baffle-plate 85 the purpose of which is to check the water flowing from the accumulating chamber and prevent it from being projected from port 83 through the outlet port 86 in the top of the accumulating 10 chamber.

Operation.

In the operation of apparatus of this 15 type, the sole aim is to give alarm when fire occurs in a building protected by a fire-extinguishing system of the type to which this invention relates. These alarms are given when the sprinkler system, or any 20 portion of it is set in operation, and it is most desirable that no alarm be given unless the sprinkler system is actually put into operation which, with proper installation, invariably takes place in the event of fire. These alarms are actuated by apparatus 25 operated by the flow of water toward open sprinklers.

It is important to prevent the operation of the alarm apparatus when the alarm valve is only intermittently momentarily 30 opened without cause necessitating an alarm, or in other words, until there is a steady continuous flow to the sprinklers, in which event the auxiliary valve will first be thrown open, and stay open, and if a sufficient 35 number of the sprinkler heads are opened, the main valve will be thrown open also. It is also important to make it inevitable that the alarm shall be given when there is really cause for it. In the operation 40 of my improved apparatus this important result is obtained as follows: With one or more sprinkler heads open the auxiliary valve 13 is thrown open and when a sufficient number of heads have opened to exceed the supply from the by-pass then the 45 main valve will also be thrown open. A clear and unobstructed passage for the water from both by-pass and main conductor 3 will be presented by the fact that the main 50 valve has been thrown to one side and the auxiliary valve with it as shown in dotted lines Fig. 2. Simultaneously the water will flow through the by-pass 12 and port 15, through piping 40 to chamber 55, through 55 port 66 raising valve 74 and closing valve 72, flood chambers 50 and 51 and reach port 86, and actuate the alarm.

Should water hammer occur the successive impulses will open the more sensitive 60 auxiliary or alarm valve and practically instantaneously equalize the pressure on the upper side of the main valve, the differential nature of which causes it to remain seated. These comparatively small spurts 65 of water will be conducted from the by-pass

12 to sub-chamber 55 and each impulse through this medium will intermittently lift valve 74 from its seat and the water will enter chamber 50, but during the intermission between the impulses the counter-weight 73 will shut valve 74 and lift valve 72 thus opening the relatively large port 68, and however rapid the impulses may be the relatively greater capacity of the port 68 as compared with inlet 66 will drain off 70 the intermittently inflowing water and prevent sufficient accumulation thereof to reach the outlet port 86. In this manner the operation of the alarm apparatus is prevented when no cause exists for an alarm. 75

What I claim is as follows:

1. In an automatic fire alarm system the combination with a water passage having a bypass; of a main valve for controlling the water passage; an auxiliary valve for controlling the bypass and constructed and arranged to open independently of the main valve; the passage and bypass being adapted to receive water from the same supply under pressure, means whereby the main valve, 90 when operating a predetermined extent automatically retains the auxiliary valve in its open position and means whereby the flow of water through the bypass operates the alarm. 95

2. In an automatic fire alarm system the combination with a water passage having a bypass; of a main valve for controlling the water passage; an auxiliary valve for controlling the bypass and constructed and arranged to open independently of the main valve; the passage and bypass being adapted to receive water from the same supply under pressure, means whereby the main valve, 100 when operating a predetermined extent, automatically retains the auxiliary valve in its open position, such means consisting of a carrier for the auxiliary valve within the path of the main valve to be engaged and retained when both valves are open; and 105 means whereby the flow of water through the bypass operates the alarm. 110

3. In an automatic fire alarm system the combination with a water passage, of a main valve for controlling the same; a supplemental water passage; an auxiliary valve for controlling the supplemental passage, both passages being adapted to receive water from the same supply under pressure, a lever carrying the main valve and fulcrumed at one side thereof and an arm pivoted at one end and extending across the main valve and carrying the auxiliary valve at its free end, and means whereby the flow of water through the supplemental passage 115 operates the alarm. 120

4. In an automatic fire alarm system the combination with a water passage, of a main valve for controlling the same; a supplemental water passage; an auxiliary valve 125

for controlling the supplemental passage, both passages being adapted to receive water from the same supply under pressure, means whereby the main valve when open to a predetermined extent retains the auxiliary valve in its open position, such means consisting of a lever carrying the main valve and fulcrumed at one side thereof and an arm pivoted at one end and extending across the main valve and carrying the auxiliary valve at its free end, the connection between the main valve and its lever consisting of a central hub or boss located within an opening in the free end of the lever and rotatably secured therein; and means whereby the flow of water through the supplemental passage operates the alarm.

5. In an automatic fire alarm system the combination with a water passage, of a main valve for controlling the same; a supplemental water passage; an auxiliary valve for controlling the supplemental passage, both passages being adapted to receive water from the same supply under pressure, means whereby the main valve when open to a predetermined extent retains the auxiliary valve in its open position, such means consisting of a lever carrying the main valve and fulcrumed at one side thereof and an arm pivoted at one end and extending across the main valve and carrying the auxiliary valve at its free end, the free end of the arm being disposed at an angle and lying normally parallel to the seat of the said auxiliary valve and the valve having a central boss located within an opening in the angular end of the arm and means rotatably fastening the same in place, and means whereby the flow of water through the supplemental passage operates the alarm.

20 6. In an automatic fire alarm system the combination with a water passage, of a main valve for controlling the same; a supplemental water passage; an auxiliary valve for controlling the supplemental passage, both passages being adapted to receive water from the same supply under pressure, means whereby the main valve when open to a predetermined extent retains the auxiliary valve in its open position, such means consisting of a lever carrying the main valve and fulcrumed at one side thereof and an arm pivoted at one end and extending across the main valve and carrying the auxiliary valve at its free end, the connection between the main valve and its lever consisting of a central hub or boss located within an opening in the free end of the lever and rotatably secured therein, the free end of the arm being disposed at an angle and lying normally parallel to the seat of the said auxiliary valve and the valve having a central boss located within an opening in the angular end of the arm and means fastening the same in place, and means whereby

the flow of water through the supplemental passage operates the alarm.

7. In an automatic fire alarm system the combination with a water passage, of a main valve for controlling the same; a supplemental water passage, an auxiliary valve for controlling the supplemental passage, both passages being adapted to receive water from the same supply under pressure, the said supplemental passage containing a duct for conducting water to the alarm and the plane of the mouth of the said duct substantially coinciding with the plane of the auxiliary valve seat, the said auxiliary valve consisting of a valvular body carrying a metal diaphragm and having a pressure equalizing port communicating with the inner side of the diaphragm, and means whereby the flow of water through the supplementary passage operates the alarm.

8. In an automatic fire alarm system the combination with a water passage, of a main valve for controlling the same; a supplemental water passage, an auxiliary valve for controlling the supplemental passage, both passages being adapted to receive water from the same supply under pressure, the said supplemental passage containing a duct for conducting water to the alarm and the plane of the mouth of the said duct substantially coinciding with the plane of the auxiliary valve seat, the said auxiliary valve consisting of a valvular body carrying a metal diaphragm and having a concavity at the inner side of the diaphragm and a pressure equalizer port communicating with the concavity, and means whereby the flow of water through the supplementary passage operates the alarm.

9. In an automatic fire alarm system the combination with a water passage, of a main valve for controlling the same; a supplemental water passage; an auxiliary valve for controlling the supplemental passage, both passages being adapted to receive water from the same supply under pressure, the said supplemental passage containing a duct for conducting water to the alarm apparatus and the plane of the mouth of the said duct substantially coinciding with the plane of the auxiliary valve seat, the said auxiliary valve consisting of a valvular body carrying a metal diaphragm and having a pressure equalizer port communicating with the inner side of the diaphragm, and means whereby the flow of water through the supplementary passage operates the alarm.

10. In an automatic fire alarm system the combination with a water passage, of a main valve for controlling the same; a supplemental water passage; an auxiliary valve for controlling the supplemental passage, both passages being adapted to receive water from the same supply under pressure, the said supplemental passage containing a

duct for conducting water to the alarm apparatus and the plane of the mouth of the said duct substantially coinciding with the plane of the auxiliary valve seat, the said auxiliary valve consisting of a valvular body carrying a metal diaphragm and having a concavity at the inner side of the diaphragm and a pressure equalizing port communicating with the concavity, and means where-

by the flow of water through the supplementary passage operates the alarm.

In testimony whereof I have signed my name to this specification in the presence of two witnesses.
